Primary Examiner — Jeffrey D Asch(74) Attorney, Agent, or Firm — William E. Pelton, Esq.; Cooper & Dunham LLP(57) CLAIM

The ornamental design for a stamp, as shown and described.

DESCRIPTION

FIG. 1 is a perspective view of a stamp, showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is another perspective view thereof.

The broken lines on the drawings are shown for illustrative purposes only and form no part of the claimed design.
